CLAIM

The ornamental design for an adjustable telescopic rod, as shown and described.

DESCRIPTION

FIG. 1 is a front, right and top perspective view of an adjustable telescopic rod, as unassembled.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG.

1.

FIG. 10 is a partial enlarged view of an area labeled 10 in FIG. 2.

FIG. 11 is a partial enlarged view of an area labeled 11 in FIG. 2; and,

FIG. 12 is a front, right and top perspective view of the adjustable telescopic rod in an assembled state.

The broken lines shown in the drawings are included for the purpose of illustrating portions of the adjustable telescopic rod that form no part of the claimed design.
